UNITED STATES PATENT OFFICE.

CHARLES R. VINQUIST, OF DENVER, COLORADO, ASSIGNOR TO HERMAN STERN, OF CLEVELAND, OHIO.

CUSHION-BEATING MACHINE.

1,034,668.

Specification of Letters Patent.

Patented Aug. 6, 1912.

Application filed July 20, 1911. Serial No. 639,684.

To all whom it may concern:

Be it known that I, CHARLES R. VINQUIST, a citizen of the United States, residing in the city and county of Denver and State of Colorado, have invented certain new and useful Improvements in Cushion-Beating Machines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in cushion beating machines of the class set forth in United States Letters Patent No. 673,635, dated May 7th, 1901.

20 My present construction, while of the general class of machines set forth in the said patent, contains a number of improvements over the said construction.

I will proceed to describe the invention in detail, reference being made to the accompanying drawing, in which is illustrated an embodiment thereof.

In this drawing: Figure 1 is a side elevation of my improved machine. Fig. 2 is a vertical section thereof taken on the line 2—2 of Fig. 3. Fig. 3 is a top plan view of the operating parts of the mechanism, being a section taken on the line 3—3 of Fig. 2. Fig. 4 is a detail view on a larger scale illustrating the combined blast 35 and suction mechanism for removing the loosened dust and dirt from the cushion. This is a section taken on the line 4—4 of Fig. 5, looking toward the right. Fig. 5 is a fragmentary top plan view, partially 40 in section, of the forward extremity of the machine, shown on a larger scale than in Figs. 1 to 3, inclusive. Fig. 6 is a section, taken on the line 6—6 of Fig. 5, or a view looking in the direction of arrow 6, Fig. 45. Fig. 7 is a top plan view of a Y-fitting connected with a suction chamber forming a part of the mechanism, the parts being shown on a somewhat larger scale than in Fig. 2 of the drawing. In this view, the 50 flexible hose pipes connected with the fitting are broken away close to the latter.

The same reference characters indicate the same parts in all the several views.

Let the numeral 5 designate a suitable 55 framework composed of upright frame bars

6, 7 and 8 on opposite sides of the machine, these upright bars being connected by top and bottom longitudinally-disposed bars 9, 10 and 11. This framework may be of any suitable construction, and further detailed explanation is therefore unnecessary.

To the top of the machine is applied a closed housing 12, which covers the entire mechanism from above, except such parts as must necessarily be exposed in order to be accessible for applying power and delivering the necessary air to the machine for operating purposes.

Journalled on the framework at the opposite ends thereof are two shafts 13 and 14, 70 upon which are made fast two pairs of pulleys 15 and 16, the pulleys 15 being at the rear extremity of the machine, and the pulleys 16 at the forward end thereof. These pulleys carry two endless belts 17, 75 suitably separated and connected by slats or transverse bars 18, the belts and slats or bars constituting an endless traveling conveyer, which is operated from a line shaft, not shown, with which is connected a belt 19, which leads to a pulley 20 fast on a transverse shaft 21, journalled on the upper part of the framework. Upon this same shaft is a smaller pulley 22, from which leads a belt 23 to a relatively large pulley 80 24 fast on a shaft 25 arranged transversely of the machine and passing between the two runs of the conveyer. On the opposite extremity of this shaft 25 is made fast a relatively small pulley 26, from which leads a 85 belt 27 to a relatively large pulley 28, fast to the shaft 14, journalled in boxes 29 at the forward end of the machine, and carrying the pulley 16 to which reference has already been made, whereby a relatively slow motion is transmitted to the conveyer, the speed of the line shaft being stepped down, so to speak, for the purpose.

The shaft 13, upon which the pulleys 15 are mounted, as heretofore explained, is 100 journalled in boxes 30, secured to the rear end of the framework. Fast on the shaft 21 is a drum 31 carrying beaters 32, composed of straps, whose inner extremities are secured to the drum; as shown at 33, by means 105 of bars 34, which are applied to the extremities of the beater straps, suitable fastening devices being passed through the said bars and the beater straps, whereby both are secured to the drum. The outer extremities 110

35 of the beater straps are each composed of a number of thicknesses of leather, whereby these extremities are made relatively heavy, thus facilitating the beating or dirt loosening function. Each series or set of beater straps is arranged in staggered relation with reference to the series of straps on each side thereof, whereby the said straps or whippers act more advantageously upon the cushion which is passing through the machine. This beater is located a suitable distance above the conveyer to allow a cushion 36 to pass below the beater, while traveling upon the upper run of the endless conveyer.

15 The beater is inclosed by the housing 12, to the opposite sides of which, below the beater, are secured, as shown at 37, the extremities of leaf-springs 38, which extend inwardly and forwardly from their fastened 20 extremities, the said springs lying in the path of the opposite side edges of the cushion 36, as the latter is traveling through the machine, from rear to front. To these springs 38 are secured extension wood members 39, which extend forward of the springs. To the forward extremities of these wood members are secured elbow-shaped metal conduits 40, one extremity of each conduit entering a flexible air carrying 25 hose pipe 41, whose opposite extremity is connected with an elbow-shaped pipe 42 connected with the air feed, as hereinafter 30 explained.

Each elbow-shaped pipe 40 is connected, 35 with its corresponding wood member 39 by means of a staple 43 or other suitable fastening device.

As illustrated in the drawing, (see Fig. 2), each spring is composed of two parts, 40 but, as this feature is not vital to the mechanism, it is not thought necessary to give these parts separate reference characters.

Mounted on the framework of the machine, directly below the forward extremities of the springs 38, is a transversely-arranged pipe 44, having perforations 45 on its upper side adapted to deliver jets of air under pressure to the lower surface of the cushion, while the latter is passing between 50 the springs 38 and while the opposite side edges of the cushion are being acted upon by the air jets from the elbow-shaped pipes 40. This transverse pipe 44 is connected with the main air feed, as hereinafter more 55 fully explained.

Pivotaly connected with the opposite sides of the housing 12, as shown at 46, are two forwardly-extending arms 47 whose forward extremities are bent inwardly, as 60 shown at 48, the outer extremities of two transverse bars 52 being connected with the forward extremities of these arms, as shown at 50. These bars 52 at their adjacent extremities are connected by two overlapping 65 curved metal bands 53, the said bands being

equipped with registering slots 54, through which is passed a fastening bolt 55, to the threaded end of which is applied a nut 56, carrying a hand piece 57, to facilitate manual adjustment. The extremities of these curved overlapping metal straps 53 are secured to their respective bars 52, as shown at 58. By virtue of this connection, the two bars may be thrown into the shape of an arch by raising their inner extremities above 75 their outer extremities, as best illustrated in Fig. 6. They may, however, if desired, be dropped to the horizontal position, or even deflected downwardly or thrown to a position the reverse of the arch-shaped arrangement, shown in Fig. 6.

To the bars 52 are secured blast pipes 59 and suction pipes 60, these pipes 59 and 60 being connected with the bars 52 by metal straps 61, one extremity of each strap being secured to its corresponding bar 52, as shown at 62, while the air blast pipes 59 are secured to the straps 61, as shown at 63, the suction pipes being secured to the forward extremity of the said straps, as shown at 64. 90 These air blast pipes and suction pipes are rigidly connected with the bars 52, and hence are adjustable therewith, as the overlapping curved bands 53 are regulated, as heretofore explained. To the bars 52 are 95 also secured the forward extremities of guide fingers 65, which are gradually curved from the bars 52, their rear extremities being uppermost. These fingers serve as guides for the cushion under treatment. 100 The air blast pipes 59 are provided with perforations 66, which are arranged to direct jets of air 67 downwardly and forwardly upon the cushion as the latter is passing underneath the said pipes, while the suction 105 pipes 60 are open, as shown at 68, directly in front of the air jets 67, whereby the dust, which is removed from the cushion by the air jets 67, is drawn into the suction pipes 60 by the suction incident to the partial 110 vacuum produced in the pipe 60 in a manner hereinafter explained. Each suction pipe 60 is equipped with a forwardly and upwardly-extending branch pipe or nozzle 69, which is connected by means of a flexible 115 hose pipe 70 with a branch 71 of a Y-shaped fixture 72, whose junction end 73 is connected with a short pipe 74 leading to a relatively small chamber 75 into which protrudes from below a relatively small air 120 pipe 76, through which air is delivered under pressure into the chamber 75 and past the inlet end of the short pipe 74, whereby suction is produced within the chamber 75 and consequently within the suction 125 pipes 60.

The chamber 75 is connected at its upper extremity with an outlet pipe 77, which leads to a vertically-disposed pipe 78 passing upwardly into a sort of stack 79 mount- 130

ed on the forward extremity of the housing. The discharge of the air into the stack 79 through the pipe 78 produces a partial vacuum within the stack, and the resulting suction has a tendency to remove any dust which might otherwise accumulate within the chamber inclosed by the housing 12.

Attention is called to the fact that the bars 52 are so connected with the forward extremities of the arms 47 as to permit the movement required in adjusting the bar members by means of the curved overlapping bands 53.

On the opposite sides of the framework 15 are formed vertically slotted members constituting yokes 80, through which pass short air pipes 81 connected at their inner extremities with double elbow-shaped pipes 82, through which air is delivered to the 20 pipes 59 from hose pipes 83. These yokes 80 permit the necessary vertical movement of the pipes 81, during the adjustment of the bars 52 to conform to the shape of the top of the cushion under treatment, as heretofore explained. The elbow-shaped pipes 82 are connected, as shown at 84, with the lower extremities of spiral springs 85, whose upper extremities are connected with the framework, as shown at 86. In this manner, 30 the combined blast pipe and suction mechanism is yieldingly supported. It may, however, be further supported by means of pins 87 passed through the yokes 80 just below the short pipes 81 when the air blast pipe 35 and suction mechanism has been properly adjusted to conform to the requirements of the particular cushion or cushions under treatment.

In order to control the suction within the 40 pipes 60, each of these pipes is equipped at its outer extremity with a disk 88, which is connected with the inner extremity of a screw stem 89, whose outer extremity is located just within the housing 12 and fashioned to receive a wrench, as shown at 90.

The velocity of the current may be increased by diminishing the size of the opening 68, and this may be accomplished by moving the disk 88 farther into the pipes 50 from their outer extremities.

The necessary air for supplying the air pipe members, as heretofore explained, and for producing the suction within the suction pipes is taken from an air feed pipe 91, provided with a valve 92. Above this valve, a branch pipe 93, equipped with a valve 94, leads to the transversely arranged perforated pipe 44, heretofore described.

Above the connection 95, between the 60 branch pipe 93 and the main pipe 91, a pipe 96 is connected with the feed pipe, as shown at 97, the pipe 96 being equipped with a valve 98 and extending rearwardly, where it is connected, as shown at 99, with a vertically-disposed pipe 100, located on one side

of the machine. The upper extremity 101 of this pipe 100 is connected with the elbow 42 on one side of the machine, with which one of the hose pipes 41 is connected. From the lower extremity of the pipe 100, a pipe member 102 extends transversely across the machine below the conveyer, and connects with the lower extremity of a pipe 103, extending upwardly, its forward extremity being connected with the elbow member 42 of 70 the other hose pipe 41, connected with one of the leaf-springs 38, as heretofore explained.

From the upper extremity of the feed pipe 91 leads a pipe 104, equipped with a valve 105. The upper extremity of the pipe 104 leads inwardly, as shown at 106, its inner extremity being connected with the vertically-disposed air jet pipe 76, whose inner extremity protrudes into the suction chamber 75, as heretofore explained. From the upper extremity of the pipe 91, a pipe 112 leads forwardly, being equipped with a valve 107. From the forward extremity of the pipe 112, the hose pipe 83 leads to the short 90 pipe 81, connected with the double elbow-shaped pipe 82, leading to one of the blast pipes 59, as heretofore explained; while, from the same extremity of the pipe 112, a hose pipe 108 leads downwardly, and then 95 transversely across the machine, its opposite extremity being connected, as shown at 109, with the short pipe 81 connected with the double elbow-shaped pipe 82 connected with the blast pipe 59 on the opposite side of the 100 machine.

It is evident that any suitable air pipe connections may be employed for furnishing the air jets and producing the necessary suction, in order to perform the various functions of the machine, as heretofore explained.

From the foregoing description, the use and operation of my improved machine will be readily understood.

Assuming that the endless conveyer is traveling, so that its upper run is moving forwardly or in the direction of arrow A in Fig. 2, the cushion 36 to be treated is placed upon the rear extremity of the upper run of the conveyer, the housing being open at the rear end of the machine, as shown at 110. The cushion is immediately carried within range of the beater straps 32, which act upon the upper surface of the cushion to loosen the dust and dirt carried thereby. 115 As soon as the cushion leaves the beater, it is brought into operative relation with the air jets issuing from the short pipes 40, which jets act upon the opposite side edges of the cushion to loosen the dust; while, at the same time, air jets from the perforated pipe 44 are delivered to the lower side of the cushion. 120 As the cushion engages the springs 38, the said springs readily yield outwardly and allow the cushion to pass through, the 130

springs being sufficiently weak to not interfere with the forward travel of the cushion upon the conveyer. After the cushion leaves the air jets from the pipes 40 and 44, as just explained, it moves into operative relation with the air blast pipes 59 and the suction pipes 60, which serve in their combined relation to remove all of the dirt loosened by the mechanism to which the cushion has 10 been previously subjected, the said dirt passing into the suction pipe 60 and thence through the branch pipes 69 and the hose pipes 70 to the Y-shaped fitting 72 and thence to the chamber 75 in which the necessary suction is produced through the instrumentality of the air jet pipe 76, whence the dirt is carried upwardly through the pipe 78 and the stack 79 and out of the machine.

20 Having thus described my invention, what I claim is:

1. In a cushion cleaning machine, an air blast pipe and a suction pipe arranged in close proximity to each other, each pipe having openings extending longitudinally thereof, and a piston slidably mounted in said suction pipe for regulating the available length thereof.

2. A machine of the class described, comprising a traveling conveyer, dust loosening means arranged adjacent the conveyer, dust removing means also adjacent the conveyer, including adjacent and co-operating air blast and suction pipes rigidly connected, pivoted arms connected with the opposite sides of said machine upon which said pipes are mounted, and means for yieldingly supporting the air blast and suction pipe construction, substantially as described.

40 3. A machine of the class described, comprising a traveling conveyer, dust loosening means arranged adjacent the conveyer, and dust removing means comprising pivoted arms mounted upon the opposite sides of the 45 said machine, bars carried by said arms and vertically adjustable in a direction transverse to the travel of the conveyer, and air blast pipes carried by the said bars and adjustable therewith.

4. A machine of the class described, comprising a traveling conveyer, dust loosening means arranged adjacent the conveyer, and dust removing means also arranged adjacent the conveyer and including pivoted arms mounted upon the opposite sides of the 50 said machine, bars whose outer extremities are movably connected with the said arms, and whose inner extremities are vertically adjustable, whereby their inner extremities are adapted to be raised or lowered above the plane of their outer extremities, air blast pipes and suction pipes adjacent each other and carried by the said bars and adjustable therewith, the bars being equipped with means for locking them in the desired 55 position of adjustment, substantially as described.

5. A machine of the class described, comprising a suitable frame, an endless traveling conveyer mounted thereon, dust loosening means arranged adjacent the conveyer and including a rotary beater, and dust removing mechanism also arranged adjacent the conveyer and forward of the dust loosening means, said dust removing mechanism 70 comprising air blast and suction means yieldingly supported and mounted to move vertically, whereby it automatically adapts itself to cushions of varying thicknesses, substantially as described.

6. A machine of the class described, comprising a suitable frame, a traveling conveyer mounted thereon, dust loosening means arranged intermediate the extremities of the machine, and adjacent the conveyer, and dust removing means located upon one extremity of said machine and also arranged adjacent the conveyer, the last named means comprising air blast and suction mechanism 85 suitably supported and mounted to move vertically, whereby it automatically adapts itself to cushions of varying thickness.

In testimony whereof I affix my signature in presence of two witnesses.

CHARLES R. VINQUIST.
